CHARLES F. KETTERING, OF DAYTON, OHIO, ASSIGNOR, BY MESNE ASSIGNMENTS, TO DELCO-LIGHT COMPANY, OF DAYTON, OHIO, A CORPORATION OF DELAWARE.

IGNITION SYSTEM.

Application filed August 5, 1918. Serial No. 248,307.

To all whom it may concern:

Be it known that I, CHARLES F. KETTERING, a citizen of the United States of America, residing at Dayton, county of 5 Montgomery, State of Ohio, have invented certain new and useful Improvements in Ignition Systems, of which the following is a full, clear, and exact description.

This invention relates to ignition systems 10 for internal combustion engines and the like, and has among its objects the provision of an ignition system including elements, a certain portion of which may be brought into effect to provide ignition to be used during 15 the engine starting operation; and a certain other portion of which, including certain elements of the first portion of the system, may be brought into effect to provide ignition during the normal running operation of 20 the engine.

One manner of carrying out this object is to provide an ignition system including an ignition unit which can be actuated mechanically to create a sparking 25 impulse, or electro-magnetically with the aid of a supply of current from any source, which may be a generator driven by the engine, where the use of a current source independent of the engine is not desired. 30 Another object of the invention is the provision of a common manually controlled device for rendering the mechanical actuating device of the ignition unit inoperative, and for rendering the electro-magnetic actuating 35 device of the unit operative, or vice versa, as desired.

Other and further objects of the present invention will be apparent from the following description of a preferred embodiment 40 thereof, reference being made to the accompanying drawings.

In the drawings:

Fig. 1 is a sectional view of the ignition unit shown in Fig. 2, the section being taken 45 on the line 1—1 Fig. 2;

Fig. 2 is a front elevation of the ignition unit embodied in the present invention together with a wiring diagram and a dia- 50 grammatic side elevation of certain parts of an internal combustion engine to which the present invention is applied; and

Fig. 3 is a fragmentary rear view of the ignition unit showing the member for controlling the mechanical and electro-magnetic

actuating devices of the unit to render either 55 of them inoperative.

Referring to the drawings 20 designates the cylinder of an internal combustion engine, in which reciprocates a piston 21 connected by means of the connecting rod 22 to 60 a crank pin 23 carried by crank shaft 24 which is mounted to rotate in bearings 25 and 26 which are suitably supported on the engine frame, not shown. A generator armature 30 is mounted on the shaft 24, and 65 cooperates with a generator field, not shown, for generating an electric current which is conducted from the armature windings to a commutator 31, or to slip rings 32 and 33. Brushes 34 and 35 cooperate with the slip 70 rings 32 and 33 to conduct current generated in the armature 30 to the primary transformer winding 36. A secondary transformer winding 37 cooperates with winding 36 to transform the current to a voltage 75 suitable for ignition purposes. Transformer winding 37 is connected by wire 38 with ignition switch 39 which is connected by wire 40 with a primary winding 41 of the ignition unit to be described. Winding 41 is connect- 80 ed by a wire 42 with an ignition timer 43 connected by wire 44 with a transformer winding 37. The circuit just described is a primary circuit of an ignition system using alternating current. It is obvious that 85 current might be supplied directly to this primary circuit from the commutator 31, if the voltage be suitable for ignition purposes. The primary circuit may also be supplied with current from a battery or other exter- 90 nal source, but as is apparent, the primary circuit may as well be energized by current supplied by the generator driven by the engine, thus making the use of an external source of current unnecessary. A secondary 95 winding 45, which includes a relatively large number of turns of fine wire surrounds the primary winding 41, and is grounded at 46 and connected by wire 47 to the spark plug 48.

50 designates as a whole, the ignition unit which comprises a supporting frame 51 which may be mounted upon the frame of the engine in any suitable manner. Mounted upon the supporting frame 51 are soft iron 105 cores 53 and 54 upon which are placed the windings 41 and 45, which have been described. 55 and 56 are permanent magnets

secured upon the cores 53 and 54 near the upper ends thereof, said magnets 55 and 56 being placed with like poles, adjacent. 57 and 58 are soft iron armatures which are 5 slidably mounted on the reduced squared end portions 59 and 60 respectively, of a bar 61. The distance between the shoulders 63 and 64 formed on bar 61 by reducing the end portions thereof is less than the length of 10 the cores 53 and 54. Springs 65 and 66 are interposed between the armatures 57 and 58 respectively, and washers 67 and 68, respectively, which are retained by means of pins 69 and 70, respectively, which pass 15 through the bar 61. Said springs 65 and 66 serve to yieldingly maintain the armatures 57 and 58 in engagement with the cores 53 and 54. The bar 61 is mounted to slide in a bearing 71 formed in the supporting frame 20 51, and is provided with a dog 72. A reciprocating bar 73 is mounted to slide in the frame 51 and carries at its lower end a roller 74 which cooperates with a cam 74^a, which is driven by the engine through the 25 gear 75 and gear 76 mounted on shaft 24. Bar 73 carries near its upper end a pivotally mounted latch 77 which is yieldingly urged by spring 78 toward the dog 72. The latch 77 is provided with a ledge 79 which 30 operates with the dog 72 in a manner to be described, and said latch 77 is provided with a bevelled surface 80 which cooperates with the bevelled surface 81 formed in the trip member 82. A cover 83 is secured to the 35 frame 51 and serves as a housing for the different parts of the unit.

The operation of the device is as follows:

When the engine is cranked, motion will be transmitted from the crank shaft 24 to 40 the cam 74^a through the gearing 76 and 75. The cam will rotate and cause the bar 73 to reciprocate in the frame 51. As the bar 73 moves upwardly, as viewed in Fig. 1, the ledge 79 on the latch 77 will engage the dog 45 72 and cause the bar 61 to move upwardly. Upward movement of the bar 61 will bring the shoulder 64 into engagement with the armature 58, thus causing the armature 58 to move away from the ends of the cores 53 and 54. During this upward movement of 50 the bar 61 the spring 65 will be compressed and the armature 57 will be firmly held against the lower ends of the cores 53 and 54. Thus a complete metallic magnetic circuit is 55 established through magnets 55 and 56, core 53, armature 57 and core 54.

Further movement of the reciprocating bar 73 will cause the camming surface 80 of the latch 77 to engage the surface 81 of the 60 trip member 82; and, as the movement of bar 73 continues, the latch 77 will release the dog 72 and will permit the bar 61 to move downwardly rapidly, by virtue of its own weight and the pressure stored in the spring 65 65. This downward movement of the bar 61

will bring the armature 58 down into engagement with the cores 53 and 54; and, after this engagement has taken place the bar 61 will continue its movement by virtue of the momentum stored in it. The shoulder 63 will engage the armature 57 and cause the movement thereof, a short distance away from the lower ends of the cores 53 and 54. When these movements of armatures 58 and 57 take place the magnetic field established 75 through the cores 53 and 54 will be short circuited by the armature 58, and the flux change will occur at a rate such as to create a sparking impulse in the winding 45 of sufficient magnitude to cause a spark to 80 jump in the spark plug 48. A spring 84 which is interposed between the lower end of a slot in bar 73 and the pin 85 mounted in frame 51 causes the bar 73 to return to its lowest position and to yieldingly maintain 85 the roller 74 in an engagement with the cam 74^a.

After the engine has become self-operative and has reached a certain speed it may be found desirable to employ some other means 90 for supplying ignition, since the noise created by the rapid movement of certain of the mechanical parts of the device and by the rapid succession of blows of the armatures 57 and 58 upon the cores 53 and 54 95 might be objectionable. To disable the reciprocating bar 73 and to turn on the ignition switch 39 a common device is provided, which, as shown in Fig. 3, consists of a lever 90 mounted at 91 upon the frame 51, 100 and provided with a cam surface 92 which is adapted to engage the pin 93 carried by the bar 73. The lever 90 is provided with operating handle 94 and carries an insulated contact member 95 extending therefrom and 105 adapted to contact with contacts 96 and 97 of the ignition switch 39. By turning the lever 90 clockwise as viewed in Fig. 3 contact 95 will engage contacts 96 and 97, and the reciprocating bar will be elevated out of 110 engagement with the cam 74^a. While the magnetic or mechanical means for varying the magnetic field about the inductive winding 45 is thus rendered inoperative, it will be observed that the elements constituting 115 the magnetic circuit are not changed or modified as regards their shape, nor are they removed out of their positions for normal operation, and hence it may be said that the normal reluctance of their magnetic circuits is not modified. Upon closing of the contacts of timer 43 current will be delivered to the winding 41 from the transformer winding 37. Thus a magnetic field will be provided for coil 45 by electro-magnetic 125 means; and upon the opening of the contacts of timer 43, the energy of this field will be changed into electrical energy in the winding 45, manifesting itself as a spark at the spark plug 48.

The ignition unit 50, when considered apart from the winding 41, constitutes a reciprocating impulse generator which can be operated at the starting of the engine and which generates an impulse the intensity of which is independent of the speed at the start. This impulse generator when thus considered alone, is not my invention, but it is to be understood that said generator constitutes a part of the structure of the disclosed embodiment of my invention. It will be understood that my invention includes the idea of creating in the region of an inductive circuit a magnetic field, either by mechanical means or by electro-magnetic means and then either mechanically or electrically producing a sudden change in the number of lines of force in the magnetic field to produce a sparking impulse. In the disclosed embodiment of this idea, I have used the impulse generator referred to, and have provided the additional winding 41 of relatively few turns of wire to serve as the primary winding of an induction coil which includes as other elements thereof the cores 53 and 54, and the winding 45 serving as the secondary winding: Current from the rotary generator driven by the engine is used to energize this induction coil, and the usual engine driven timer is employed to control the delivery of current to the coil and the interruption of the current to create the sparking impulse.

Thus it will be apparent that the ignition system embodying the present invention possesses the advantages of an impulse generator ignition system for supplying ignition at low engine speed, and also the advantages of a silent operating battery-type system without the disadvantage of providing a separate storage battery or other source of current independent of the engine.

While the form of mechanism herein shown and described constitutes a preferred embodiment of one form of the invention, it is to be understood that other forms might be adopted, and various changes and alterations made in the shape, size, and proportion of the elements therein without departing from the spirit and scope of the invention.

What I claim is as follows:

1. In an ignition system, the combination with an inductive circuit; of a magnetic path through the circuit; and electrical means and mechanical means for intermittently creating and destroying a magnetic field in the region of the circuit, whereby to induce a sparking impulse in the inductive circuit; and selective means for rendering either of said means inoperative, said mechanical means being rendered inoperative merely by arresting it in one of its normal operating positions.

2. In an ignition system, the combination with an inductive circuit; of a magnetic

path through the circuit; electrical means and mechanical means for intermittently creating and destroying a magnetic field in the region of the circuit, whereby to induce a sparking impulse in the inductive circuit; and means for rendering the mechanical means inoperative, said mechanical means comprising a magnetic circuit and being capable of being rendered inoperative while maintaining the normal reluctance of said magnetic circuit.

3. In an ignition system, the combination with an inductive winding; of a source of magnetism; a core cooperating with the winding for conducting and concentrating magnetism from the said source in the region of the winding; a second inductive winding cooperating electro-magnetically with the core and first named winding; a source of current and an ignition timer adapted to be connected with the second inductive winding; means normally short-circuiting the source of magnetism from said core, but mechanically operated for interrupting the short-circuit; means for rendering said last named means inoperative to interrupt said short-circuit and for connecting the second named inductive winding with the timer and current source whereby a sparking impulse may be created electro-magnetically in the first inductive winding.

4. In an ignition system, the combination with an inductive winding and a permanent magnet; a core cooperating with the winding for conducting and concentrating magnetism from the permanent magnet in the region of the winding; means normally short-circuiting the flux of the permanent magnet from the core but mechanically operated for interrupting the short-circuit; a second inductive winding cooperating with the core; an ignition timer; a source of current adapted to be connected with the timer and the second inductive winding; and means for rendering the first named means inoperative to interrupt the short-circuit and for bringing the second named inductive winding into operation whereby to create a sparking impulse in the first named induction winding.

5. In an ignition system, the combination with an inductive winding; of a permanent magnet; cores cooperating therewith and with the winding for conducting magnetism from the permanent magnet to the winding and for concentrating said magnetism in the region of the winding; a movable armature cooperating with the cores for completing the magnetic circuit through the cores; a second movable armature for short-circuiting the magnetism of the permanent magnet away from the cores; a second inductive winding cooperating with the cores and the first inductive winding; an ignition timer; a source of current adapted to be connected

with the timer and with the second inductive winding; a reciprocating member actuating the armatures to interrupt intermittently the short-circuit of the flux of the permanent magnet whereby intermittently to energize said cores; means for rendering the reciprocating member inoperative and for connecting the second inductive winding with the timer and source of current whereby a 10 sparking impulse may be created in the first named inductive winding.

6. In an ignition system for internal-combustion engines, the combination with an inductive circuit; of a permanent magnet; a 15 source of current; electro-magnetic means cooperating with the current source and the inductive circuit for intermittently creating a magnetic field in the region of said circuit; and means for intermittently causing the 20 permanent magnet to produce a magnetic field in the region of the inductive circuit; and selective means for rendering either of 25 said means inoperative while maintaining the normal reluctance of their magnetic circuits.

7. In an ignition system for internal-combustion engines, the combination with an inductive circuit; of a permanent magnet; a source of current; electro-magnetic means 30 cooperating with the current source and the inductive circuit for intermittently creating a magnetic field in the region of said circuit; and means for intermittently causing the permanent magnet to produce a magnetic field 35 in the region of the inductive circuit; and

means for rendering said last named means inoperative and the electro-magnetic means operative, or vice versa, while maintaining the normal reluctance of their magnetic circuits.

8. In an ignition system, the combination with an inductive circuit; of a magnet; means for periodically shifting the magnetic flux of the magnet into cooperative relation with the inductive circuit whereby to induce 45 a sparking impulse in the inductive circuit; means comprising a second inductive circuit for intermittently creating a magnetic field in cooperative relation with the first-mentioned inductive circuit whereby to induce a sparking impulse therein; and selective means for rendering either of said means inoperative, while maintaining the normal reluctance of their magnetic circuits.

9. In an ignition system, the combination 55 with an inductive circuit; of a magnetic path through the circuit; and electrical means and mechanical means for intermittently creating and destroying a magnetic field in the region of the circuit, whereby to 60 induce a sparking impulse in the inductive circuit; selective means for rendering either of said means inoperative; and timer mechanism cooperating only with said electrical means.

In testimony whereof I affix my signature.
CHARLES F. KETTERING.
